UNITED STATES PATENT OFFICE.

ABIJAH TAYLOR, OF CHICAGO, ILLINOIS, ASSIGNOR OF ONE-HALF TO
JAMES WELCH, OF WEBSTER CITY, IOWA.

ROTARY ENGINE.

SPECIFICATION forming part of Letters Patent No. 634,511, dated October 10, 1899.

Application filed May 2, 1898. Serial No. 472,723. (No model.)

To all whom it may concern:

Be it known that I, ABIJAH TAYLOR, of Chicago, in the county of Cook, in the State of Illinois, have invented certain new and useful Improvements in Rotary Engines, of which the following is a specification.

This invention relates to improvements in rotary steam-engines, and more particularly to that type of such engines adapted to use steam expansively.

The object of the invention is to provide an improved construction in engines of the character referred to; and it consists in the matters hereinafter set forth, and particularly pointed out in the appended claims.

In the accompanying drawings, Figure 1 is a longitudinal sectional elevation of a rotary engine embodying my invention, the section being taken on line 1 1 of Fig. 2. Fig. 2 is a transverse sectional elevation of the same, taken on line 2 2 of Fig. 1. Fig. 3 is a similar view taken on line 3 3 of Fig. 1. Fig. 4 is an end elevation of the rotary piston removed from the cylinder. Fig. 5 is a side elevation of the same. Fig. 6 is a longitudinal section of the rotary piston and shafts, taken on line 6 6 of Fig. 2. Fig. 7 is a side elevation of the same, taken from the same point of view, the piston-wings being removed. Fig. 8 is an outside view of one of the piston-wings. Fig. 9 is an enlarged detail of a portion of the end of the same. Fig. 10 is an inner view of one of the exterior plates of the piston. Figs. 11 and 12 are detail views of the inner shaft, showing, respectively, the steam and exhaust openings. Figs. 13 and 14 are similar views showing steam-port openings of shapes somewhat modified from those shown in Fig. 11. Figs. 15 and 16 are detail sections on lines 15 15 and 16 16 of Fig. 1. Fig. 17 is a detail view of a modified form of steam-tight packing.

A designates the base-plate of the engine, B supporting-standards secured to said base-plate and rising above the same, and C the steam-cylinder, which is revolubly supported at the upper end of the standards B by means of inward-projecting bosses B', which engage central circular apertures c, formed in the heads C' of said cylinder. Within the cylinder C is provided a cylin-

drical piston D of less diameter than the interior of the cylinder C, but equal in length thereto, each end of said piston closely engaging the adjacent cylinder-head C'. Said piston D is rotatively supported within the cylinder C by means of a hollow shaft E, which engages a longitudinal central bore in said piston and is rigidly secured therein by means of keys e or in any other suitable manner. The ends of the shaft E extend out of the cylinder C through apertures c in the heads C' and, as herein shown, are supported in suitable journal-bearings B², formed in the bosses B', said bearings B² being located sufficiently eccentric to the common axis of said bosses B' and cylinder C to bring a portion of the perimeter of the piston D into contact with the interior of the cylinder. In this instance said journal-bearings are located vertically above said common axis of the bosses and cylinder, bringing the piston D into contact with the interior surface of the cylinder along a line at the top of each and in a vertical plane through their axis. Said rotary piston D is provided at its perimeter with one or more extensible wings D', (in this instance four in number,) herein shown as pivoted along their front edges to the perimeter of the piston and adapted to fold into convenient recesses in said piston as they approach and pass the point of contact of said piston with said interior surface of the cylinder, said wings D' being formed with curved exterior surfaces, so that when folded into their respective recesses they form a continuation of the normally-cylindric perimeter of the piston D. Between each two adjacent wings the piston D is provided with a radial port d, leading from the exterior of the piston to the interior of the hollow shaft E. As herein shown, the said ports d extend nearly the full length of the piston D and are placed at right angles to each other, the outer ends of said ports being directly beneath the wings D'. The steam admitted forces the wings outward against the wall of the cylinder and sets the piston to rotating, and since the cylinder itself is free to revolve the friction between it and the piston and piston-wings is substantially reduced to the friction of rolling contact. The use of gearing between the cylin-

der and piston to maintain such rolling contact is, however, avoided, as tending toward complication and unnecessary friction losses.

Extending longitudinally through the hollow shaft E is a closely-fitting non-rotating tube or pipe F, which is divided by a partition F' into two separate compartments F² and F³, adapted to communicate, respectively, with the steam supply and exhaust. Said partition F' extends obliquely across the tube F between points adjacent to the opposite ends of the piston D, and said tube F is provided on the opposite sides of said partition with port-openings f and f', the former opening 15 out of the steam-chamber F² and the latter out of the exhaust-chamber F³ of the pipe F. The shape of said port-openings may be varied as desired. In Figs. 11, 13, and 14 I have shown three different shapes and arrangements 20 of the steam-openings f, that shown in Fig. 13 being the one used in the particular engine illustrated. The exhaust-opening f' will ordinarily be made in the shape of a single elongated aperture, as shown in Fig. 12. 25 Obviously with such construction each of the ports d will, by the rotation of the piston D, be brought into communication alternately with the steam and exhaust openings f and f' in the tube F. The steam-openings f being placed on the upper and forward side of the pipe, as shown in Fig. 2, steam will be first admitted to each port d substantially as 30 said port passes the point of contact of the perimeter of the piston with the interior of the cylinder and will continue to be admitted until the inner end of the port d has passed by the steam-opening f. The steam thus admitted to the port d will obviously force out the adjacent piston-wing D', maintain the 35 outer edge of said wing in constant contact with the inner wall of the cylinder C, and cause the piston D to rotate, said steam acting by direct pressure up to the point of cut-off and continuing thereafter to act by expansion until the port d shall have reached the exhaust-opening f, whereupon said steam will pass off through the exhaust-passage F³. As herein shown, the said exhaust takes place shortly after the wing D' reaches its lowermost position. Obviously each of the wings D' will in succession pass through the cycle of action thus described, each receiving a new actuating impulse at each revolution, and as each of the wings D' acts through substantially half of each revolution it will be obvious that the piston D and shaft E will at every moment be receiving the rotation influence of two of said wings. A suitable driving-pulley G, keyed or otherwise rigidly secured to 50 the projecting end of the shaft E, furnishes a convenient means of taking off the power. Obviously the other end of the shaft E might also be extended and provided with a second driving-pulley.

65 It will be evident that with the construction above described the cut-off may be made to take place either earlier or later, as de-

sired, by oscillating the tube F, so as to vary the position of the steam-opening f. In this instance I have provided means for rocking 70 said tube F by hand, said means consisting, as herein shown, of a hand-lever F⁴, clamped to the projecting end of the tube F and provided at its lower end with a thumb-screw F⁵, which engages a nut F⁶, sliding in the arc-shaped groove b in the adjacent face of the adjacent standard B. When the thumb-screw F⁵ is loosened, it will be obvious that the tube F may be readily oscillated by the lever F⁴ to provide either a late or early cut-off, as 80 desired. When the proper adjustment is obtained, the parts may be locked in position by again tightening the thumb-screw. Obviously such regulation might, however, be accomplished automatically by operatively connecting any suitable form of governor with the tube F to oscillate the same. It will be evident that with such construction any degree of expansion of the steam may be obtained by regulating the amount admitted behind 85 each piston-wing at each revolution. Furthermore, owing to the crescent shape of the space between the piston D and cylinder C, I am enabled, by providing the admission-point at the tapered end of said space, to secure a very 90 clean cut-off, while admitting but a small amount of steam. By hinging the piston-wings at their front edges they are drawn around the cylinder with but little friction and have no opportunity or tendency to bind 95 or stick.

Referring here more particularly to the details of the construction herein illustrated, the standards B consist of two metallic bars provided with inwardly-extending lower 105 ends adapted to overlap each other, the overlapping portions being herein shown secured together and to the base-plate A by means of a clamping-bolt a. Said inwardly-extending lower ends are also herein shown as perforated for the passage of the foundation-bolts a', by which means they are further securely held at the base-plate and foundation. The upper ends of said standards B are shown as bent inwardly to support the bosses B', which 110 as a simple and efficient construction are of babbitt or similar metal, secured to the inwardly-extending ends of the standards by being cast about the same. In this instance the bosses B' are cut off on a horizontal plane 115 through the axis of the shaft E, the portion above said plane being omitted and the bearing-surfaces B² for said shaft being merely half-boxes formed in the lower portions of said bosses. Obviously, however, the upper 120 portions of said bosses might be filled in, if desired.

As a further improvement that part of each of the bosses B' immediately adjacent to its bearing-surface B² is formed of a separate 125 piece or box B³, recessed in the body of the boss. A key B⁴ is inserted in a suitable recess beneath the center of the box B³ and by driving in said keys compensation may be

made for the wear of the shaft E in its bearings. Such construction also provides means for adjusting the contact between the upper portion of the piston D and the interior of the cylinder C, it being obvious that by lifting the shaft more or less by means of the keys B⁴ the piston may be made to engage the cylinder along the line of contact with a greater or less degree of pressure, as desired. It is designed in practice to have such pressure sufficient to maintain a constant rolling contact between the piston and cylinder, whereby their peripheral speeds will be equal and the friction of the parts thereby reduced to a minimum. Obviously in such case the cylinder practically rests upon the piston D, and its weight is supported by the babbitt bearing-surfaces B².

The cylinder-heads C' are herein shown as adjustably secured in place by being screwed into the ends of the cylinder C, set-screws c' being provided, by means of which they may be locked when in the desired position. In practice said heads are screwed in until they strike the ends of the piston D, then unscrewed a fraction of a turn to permit free movement of the parts without material leakage, and finally are locked in place by the set-screws c'. To further provide against leakage between the heads C' and the ends of the piston D, said heads are herein shown recessed on their inner faces adjacent to the apertures c to receive annular packings c², which engage the ends of the piston D and are pressed against the same by suitable springs c³, provided in suitable recess c⁴ and tending to force said packing inward. It is obvious, however, that such packing might be provided on ends of the piston D and made to engage the faces of the heads C', if so desired. Said heads C' are also herein shown as provided with annular flanges C², surrounding the central openings c and furnishing an additional length of bearing on the bosses B'. As a convenient construction of the piston D the latter is herein shown as formed of a hollow cylindrical shell D³, having end walls D⁴ and radial rib-walls D⁵, connected at their inner ends by a suitable hub D⁶, within which the shaft E is keyed, the ports d, hereinbefore described, leading from the exterior of the shell D³ to the interior of the hub D⁶ through the radial walls D⁵. Longitudinal plates D⁷, secured to the outside of the shell D³ by means of screws d' or in other suitable manner, serve to separate the piston-wings D', and said wings are adapted to fold within the spaces between said plates D⁷. Said piston-wings D', as herein shown, are made of uniform thickness equal to the thickness of the plates D⁷ and are bent to the radius of the shell D³, so that when folded down upon the same their outer faces form a substantially continuous cylindrical surface 65 with the other faces of said plates D⁷.

To provide a convenient hinge connection between the wings D' and the shell D³, said

wings are herein shown as provided along their forward edges with inwardly-projecting longitudinal ribs D⁸ of substantially circular cross-section, which engage corresponding grooves in the shell D³ and are movably held therein by the overlapping edges of the plates D⁷. Said ribs D⁸ are herein shown as formed by wrapping one edge of a plate d² about an inner rod or core d³ and then slipping a slotted brass tube or bushing d⁴ over the wrapped edge of said plate d², leaving the straight edge of said plate projecting through the slot of said bushing. Said free edge of the plate d² is then readily attached to the beveled edge of the wing D' by screws d⁵ or in other suitable manner.

To permit the inner tube or pipe F and inclosing shaft E to fit closely in those parts adjacent to the steam and exhaust opening f and f' and at the same time to reduce the friction of such parts to a minimum, I have herein shown said shaft E as recessed to receive a bushing e' of babbitt or similar material, said bushing being slightly longer than the steam and exhaust openings f and f' and being apertured opposite the ports d to permit the free action of the same. Leakage between said tube and outer shaft is further prevented at each end by a stuffing-box E', herein shown as having a screw-threaded engagement with the inner tube F and provided with an inward-projecting sleeve E², inclosing the end of the shaft E. The end surface of said shaft E is cut in on a bevel to receive the beveled end of an inner bushing E³, of babbitt or similar material, provided with the stuffing-box E' and forced against the end of the shaft by suitable springs e², placed behind said bushing. By screwing up the stuffing-box E' the bushing E³ may be forced against the end of the shaft with any desired degree of pressure, causing the thin beveled edge of the bushing to form a steam-tight engagement with both the inner tube and the outer shaft.

In Fig. 17 I have shown a modified form of packing which may be employed to prevent leakage between the shaft E and the inner tube F. In this construction the said inner tube F is provided with an annular recess, within which is inserted a section b² of closely-coiled spring-wire rectangular in cross-section and made of hard-drawn brass or similar material. Said coil f² when placed within the annular recess and inserted within the shaft E will expand or spring outward against the inner surface of said shaft and form a steam-tight joint therewith.

While primarily intended for use with steam as the actuating fluid, it will be obvious that my improved engine may be operated by and will act with equally great efficiency with compressed air or gas, the operation under such circumstances being precisely the same as when steam is employed.

I claim as my invention—

1. A rotary engine comprising a rotatably

supported cylinder, a cylindric piston rotatably mounted within and eccentrically of said cylinder and in contact with its cylindric surface at one point, and folding piston-wings 5 hinged to said piston and adapted to fold in flush with the cylindric surface thereof, substantially as described.

2. A rotary engine comprising a cylinder, journal-bearings rotatably supporting said cylinder, a cylindric piston rotatably mounted within and eccentrically of said cylinder and in contact with its cylindric surface at one point, piston-wings hinged to the piston and adapted to fold flush with the cylindric 15 surface thereof, a tube extending through an axial aperture in said piston and provided with steam and exhaust passages, and radial ports in the piston adapted to communicate alternately with said steam and exhaust 20 passages as the piston rotates, substantially as described.

3. The combination with a supporting frame, of the cylinder C rotatably journaled

in said frame, the cylindric piston D mounted upon the shaft E which is also rotatably journaled in said frame but eccentrically with relation to the cylinder C so that the cylindric surfaces of the piston and cylinder are in contact at one point, piston-wings D' hinged to said piston, ports d leading through from the 25 interior of the hollow shaft to the exterior of the piston beneath the folding wings, tube F extending through the hollow shaft and provided with steam and exhaust ports f and f', and with the diagonal diaphragm F' dividing 30 the tube between said steam and exhaust ports, and means for oscillating said tube to vary the point of cut-off, substantially as described.

In testimony that I claim the foregoing as 40 my invention I affix my signature in presence of two witnesses.

ABIJAH TAYLOR.
